UNITED STATES PATENT OFFICE.

JAMES WILLIAMS, OF VIENNA, GEORGIA.

WASHING MACHINE.

Application filed August 17, 1925. Serial No. 50,727.

To all whom it may concern:

Be it known that I, JAMES WILLIAMS, a citizen of the United States, residing at Vienna, in the county of Dooly and State 5 of Georgia, have invented a new and useful Washing Machine, of which the following is a specification.

This invention relates to washing machines and the object of the invention is to 10 so construct a machine of this character that the clothes may be rubbed while they are boiling.

Another object is to construct a machine 15 of this character which is simple and cheap to manufacture, easy to operate and which may be repaired at a minimum cost should any of the parts be broken.

With the foregoing and other objects in view which will appear as the description 20 proceeds, the invention resides in the combination and arrangement of parts and in the details of construction hereinafter described and claimed, it being understood that changes in the precise embodiment of the invention herein disclosed may be made within 25 the scope of what is claimed without departing from the spirit of the invention.

In the accompanying drawings:—

Figure 1 represents a side elevation of a 30 machine constructed in accordance with this invention;

Figure 2 is a top plan view thereof;

Figure 3 is a longitudinal section taken on the line 3—3 of Figure 2; and

Figure 4 is a transverse section taken on the line 4—4 of Figure 1.

In the embodiment illustrated, a hollow base 1 is shown designed to form a heater for the machine and which has rising from 40 one end thereof a smoke stack 2, the opposite end from the smoke stack being open to permit feeding of the fire when the machine is used out of doors and wood burned.

Mounted on the base 1 is a water container 45 10 which is preferably constructed of sheet metal and which is open at its top and has mounted in the bottom thereof a rubbing board 11 which is provided with apertures 12 for the passage of the water therethrough which will let the boiling water in the vat or tank through to the clothes while the scrubbing is in process.

Mounted to cooperate with the stationary 50 rubbing board 11 is a movable rubbing board 13 which has a corrugated scrubbing face

14 similar to an ordinary wash board which cooperates with the wash board 11.

A post 15 rises from the board 13 and extends above the top of the tank 10 where it is connected with an operating lever 16 60 fulcrumed intermediate its ends on one side edge of the tank as is shown clearly in Figures 1 and 2. This fulcrum 17 is in the form of a bolt having a washer 18 arranged thereon between the lever and the tank head 65 and equipped with a wing nut 19 for removably securing the lever in place.

The end of the lever which is connected with the post 15 has a longitudinally extending slot 20 through which the upper end 70 of the post extends and is secured by a nut 21.

A coiled spring 22 connects the upper end of post 15 with the side of the tank opposite to that on which the lever 16 is mounted as 75 is shown clearly in Figure 2. This spring exerts its tension to assist in the rubbing operation of the movable rubber, the lever being actuated to move the rubber in one direction and the spring operating to move 80 it in the opposite direction.

It will thus be seen that when heat is applied to the base 1 the water in the tank 10 will be heated and may be used boiling while the scrubbing operation is going on, 85 the cleansing power of which is much greater than the steam.

In the use of the invention the clothes are placed in the tank 10 and the rubber 13 lowered onto them, it being understood that 90 water has first been placed in the tank and heated to the desired temperature. The lever 16 is then swung back and forth which causes the rubber 13 to reciprocate over the clothes and thoroughly cleanse them. 95 The cooperation of the spring 22 with the lever greatly facilitates the operation thereof and requires very little power to actuate the lever.

While this washing machine is shown 100 mounted on a base heater or heating base it is of course to be understood that it is not permanently fixed thereto and may be placed on a stove or any other source of heat supplied thereto sufficient to cause boiling of the water in the tank 10.

I claim:—

In a washing machine, a water containing tank having a corrugated bottom forming a stationary rubber, a movable rubber 110

mounted on said bottom and having a post rising therefrom and extending above the top of the tank, a lever fulcrumed on said tank intermediate the ends of the lever, the 5 inner end of said lever having a slot and pin connection with said post, and a coiled spring connected with said post and with

said tank to assist in the operation of the movable rubber.

In testimony that I claim the foregoing 10 as my own, I have hereto affixed my signature.

JAMES ^{his} WILLIAMS
